ROTARY FLUID PUMP OR MOTOR

Maynard E. Estey, Canandaigua, N. Y.

Application April 3, 1939, Serial No. 265,681

5 Claims. (Cl. 103—160)

This invention relates to a fluid pump or motor of the rotary type.

The main object of the invention is to produce a rotary pump or motor which is simple, durable and economical in construction and which is positive, accurate and dependable in operation at high speed and/or at high pressure.

Another object of the invention is to provide a pump or motor of the above mentioned character with control means which may be readily actuated at any time during the operation of the pump or motor for varying the capacity thereof.

Still another object of the invention resides in the provision of a rotary fluid pump or motor in which a reversal in the direction of operation of the same may be produced.

More specifically, my invention contemplates the provision of a pump casing having a rotor chamber therein and intake and discharge fluid passages communicating with the rotor chamber, the provision of a rotor having a compression or piston chamber and rotatably mounting the rotor in the rotor chamber so as to bring the compression or piston chamber into successive communication with the fluid passages.

A further object of the invention is to provide adjustable means associated with the pump casing for maintaining the inlet and exhaust passages in substantially fluid-tight connection with the piston chamber of the rotor and to compensate for wear.

In carrying out the above objects, I have provided two pistons, one of which is reciprocatively mounted in the compression or piston chamber of the rotor. This piston in turn is provided with a compression or piston chamber which reciprocatively receives the second piston therein, said second piston being rotatably supported in eccentric relation with the axis of rotation of the rotor so that upon rotation of the rotor a relative reciprocal movement of the compression or piston chambers and the pistons mounted therein is produced.

A further object is to provide simple and durable control means which may be readily operated either manually or automatically for varying the relative positions of the axes of rotation of the second piston and the rotor to control the capacity of the motor or pump and/or the direction of operation thereof.

A still further object of the invention is to provide the pistons with pressure plates or shoes for maintaining a fluid-tight connection between relatively movable surfaces of the pistons and the piston chambers.

I attain these objects by mechanism illustrated in the accompanying drawings, in which:

Figure 1 is a plan view of a pump or motor embodying the various features of this invention.

5 Figure 2 is a vertical longitudinal sectional view taken substantially on line 2—2, Figure 1, the lower portion of the case being broken away.

Figure 3 is a transverse vertical sectional view taken substantially on line 3—3, Figure 2.

10 Figure 4 is a perspective view, partly in section, illustrating adjacent portions of a control shaft and a supporting or guide block associated therewith.

Figure 5 is a perspective view, partly in section, 15 illustrating a bearing sleeve adapted to be associated with the guide block shown in Figure 4 for rotatably supporting a piston.

Figure 6 is a horizontal sectional view through 20 one end portion of the pump case taken substantially on line 6—6, Figure 3, illustrating my novel construction for providing the inlet and discharge passages of the pump.

Figure 7 is a transverse sectional view taken 25 substantially on line 7—7, Figure 6, illustrating one of the end plates of the pump casing in inner face view and on a reduced scale.

Figures 8, 9 and 10 are more or less diagrammatic inner face views of an end plate of the rotor illustrating the same in different angular 30 positions with respect to the inlet and discharge passages of the pump casing.

Figure 11 is a transverse sectional view through the rotor similar to Figure 3 illustrating the rotor rotated one-eighth of a revolution from the position shown in Figure 3 with the pistons shown in their positions with respect to each other and to the piston chamber of the rotor.

Figure 12 is a transverse sectional view similar to Figure 11 illustrating the pistons in their respective positions when the rotor and pistons are moved substantially one-quarter of a revolution from the position illustrated in Figure 3.

Figure 13 is a detail sectional view taken on line 13—13, Figure 7, illustrating an adjustable take-up for maintaining a fluid-tight connection between the inlet and discharge passages and the rotor during the rotation of the rotor.

Figure 14 is a perspective view of a piston pressure plate or shoe.

50 Figure 15 is a longitudinal vertical sectional view similar to Figure 2, illustrating a modified form of my novel pump structure.

Figure 16 is a transverse sectional view taken substantially on line 16—16, Figure 15.

55 Figures 17 and 18 are transverse sectional views

similar to Figure 16 illustrating the rotor and pistons moved substantially one-eighth and one-quarter of a revolution, respectively, from the positions thereof shown in Figure 16.

Figure 19 is a longitudinal sectional view taken on line 19—19, Figure 16.

The pump or motor, illustrated in Figures 1 to 13 inclusive of the drawings, comprises a sectional case 20 having a cylindrical central body portion 21 and two end plates 22 and 23 secured to opposite sides of the body portion as by bolts 24, the plates 22 and 23 being provided with central bearing members 25 and 26, respectively. A drive shaft 27 is rotatably mounted in the bearing member 26. The outer end of the bearing 26 may, as shown in Figure 2, be provided with a stuffing box 28 for preventing leakage of fluid around the shaft 27.

The chamber 30 of the pump casing 20 is circular in cross section and has mounted thereon a rotor 31. This rotor, as shown, is composed of a central cylindrical body portion 32 and end plates 33 and 34 connected to the body at opposite sides thereof by a plurality of transversely extending pins or rods 35. The end plates 33 and 34 are provided with outwardly extending centrally disposed bosses 33' and 34', respectively, which are journaled in suitable ball bearing members 37 mounted in recesses provided in the inner faces of the case end plates 22 and 23. The width of the rotor 31 is such that it has a close running fit in the case chamber 30, the rods 35 being removably received in suitable aligned openings provided in the body portion 32 and side plates 33 and 34 for maintaining the body portion and side plates against relative rotary movement.

In order that motion may be transmitted to the rotor, the shaft 27 has the inner end thereof secured to the adjacent rotor plate 34 as by a key 39, Figure 2. The rotor body 32 is provided with a substantially rectangular opening 40 extending longitudinally therethrough in symmetrical relation therewith. This opening forms a piston chamber between the rotor end plates 33 and 34 for receiving a pair of pistons 41 and 42 therein. These pistons are substantially rectangular members each having an axial length substantially equal to the axial length of the piston chamber 40 to reciprocate in said chamber with a close sliding fit between the end plates 33 and 34 of the rotor. The width of the piston 41 is substantially equal to the thickness of the piston chamber 40 and the thickness of the piston 41 is appreciably less than that of the corresponding width of the piston chamber 40 so that the piston may have a predetermined reciprocative movement through the piston chamber in one direction while being maintained against reciprocative movement in said chamber in a direction normal to the first mentioned direction.

The piston 41 is provided with a rectangular opening 44 extending axially therethrough in symmetrical relation therewith which forms a piston chamber for receiving the piston 42 therein. The width of the piston 42 and chamber 44 in one direction normal to the length thereof is substantially equal. The width of the piston 42 is substantially equal to the thickness of the piston chamber 44, while the thickness of said piston is considerably less than the breadth of chamber 44 so that the piston may have a predetermined reciprocative movement in the chamber in the direction of the major transverse axis of the chamber.

The width or major transverse axis of the pis-

ton chamber 44 is arranged in right angular relation to the direction of reciprocative movement of piston 41 in chamber 40 so that the reciprocative movements of the pistons 41 and 42 are substantially normal to each other. The inner piston 42 is rotatably mounted upon a bearing sleeve 46 which extends centrally through the piston from one end thereof to the other between the end plates 33 and 34 of the rotor 31.

10 The bearing sleeve 46 is provided with a longitudinally extending opening 47 arranged in eccentric relation to the sleeve. The opening 47 is rectangular in cross section and slidably receives therein a guide or supporting block 48 which in turn receives one end 49 of a control shaft 50 journaled in the bearing member 25 in substantially coaxial relation with the shaft 27. The block 48 has a cylindrical bearing portion 51 at one end which is rotatably received in the hub portion 33' of the rotor end plate 33, a central portion 52 extending through the piston chamber 40 of the rotor 32 between the end plates 33 and 34 and a cylindrical reduced end portion 53 which is journaled in the end plate 34 adjacent the inner end of the shaft 27, as shown in Figure 2.

The width of the central portion 52 of the guide block is substantially equal to the width of the opening 47 provided in the bearing sleeve 46 so that the guide block may have free movement through the opening 47 upon relative lateral movement of the guide block and bearing sleeve. The guide block 48 is preferably provided, as shown in Figure 2, with an annular outwardly disposed flange 54 arranged in a suitable recess provided at the inner end of the bearing member 25 adjacent the hub 33' of the end plate 33 for maintaining the guide block against axial movement with respect to the casing 20 and rotor 31.

40 The outer end portion 56 of the control shaft 50 is preferably of greater diameter than the inner end portion 49 and extends outwardly through a stuffing box 57 provided on the outer end of the bearing member 25 and has secured thereto a handle 58 by which the shaft may be rotated. 45 The shaft 56 is also adapted to be moved axially with respect to the bearing member 25 and a guide block 48 and for this purpose is provided with an annular peripheral recess 60 adjacent the outer end thereof which receives a pair of diametrically disposed studs 61 carried in the forked end 62 of a lever 63 pivotally connected at 64 intermediate the ends thereof to a bracket 65 carried by the bearing 25, as shown in Figure 1.

The inner end portion 49 of the control shaft 55 is provided with a pair of pins 67 arranged in spaced relation to each other longitudinally of the shaft and which extend diametrically therethrough. The pins 67 extend outwardly beyond the shaft portion 49 through elongated guide slots 68 provided in opposite sides of the guide block portion 52 and into elongated cam slots 69 provided in the bearing sleeve 46. There are two pairs of guide slots 68, one pair for each pin 67. The guide slots of each pair extend longitudinally 60 of the block portion 52 substantially parallel with the axis thereof so that the pins 67 may readily move through said slots during the axial movement of the shaft 50. Likewise, there are two pairs of cam slots 69 provided in the bearing 65 sleeve 46 one pair for each pin 67. These cam slots 69 extend in angular relation to the axis of the bearing sleeve and, therefore, to the guide slots 68 provided in the block 48.

70 It will be understood that during the movement of the pins 67 longitudinally through the

slots 68 and 69, the bearing sleeve 46 will be caused to move laterally with respect to the guide block and control shaft 50 in one direction or the other by the camming action of the pins 67 and slots 69 upon said sleeve, depending upon the direction of axial movement of the control shaft.

It will also be understood that during the rotation of the control shaft 50 a corresponding rotary movement of the guide block 48 and bearing sleeve 46 will be produced thereby due to the engagement of the pins 67 in the slots 68 and 69. This rotary movement of the bearing sleeve 46, guide block 48 and control shaft 50 produces a corresponding lateral movement of the pistons 41 and 42 through the piston chamber 40 from a position at one side of the axis of rotation of the rotor 31 to a corresponding position at the diametrically opposite side of said axis of the rotor. This change in the position of the pistons with respect to the piston chamber 40 alters the action of the pistons so that the direction of flow of the fluid through the pump is reversed due to the coaction of said pistons with the fluid passages associated with the piston chamber 40 in a manner which will hereinafter more clearly appear.

One of the end plates, as 34, of the rotor 31 is provided with two pairs of fluid ports 71 and 72 extending transversely therethrough for alternately connecting the piston chambers 40 and 44 with a pair of fluid passages 73 and 74 provided in the case 20. The ports 71 are elongated substantially rectangular openings arranged at diametrically opposite sides of the center of the rotor plate 34 in substantially parallel relation to each other, as shown in Figure 8. These ports are arranged substantially equal distances from the center of the plate 34 and extend through said plate substantially normal to the inner and outer side surfaces thereof as shown in Figure 2.

The ports 72 are also elongated substantially rectangular shaped openings which are arranged at diametrically opposite sides of the center of the plate 34 in right angular relation to the ports 71. The ports 72 are arranged at opposite sides of the center of the plate 34 substantially equal distances from said center and intermediate the ports 71, as illustrated in Figure 8. The ports 72 extend through the plate 34 in angular relation to the inner and outer side surfaces thereof, as shown in Figure 6, the inner ends of the ports 72 being spaced a less distance from the center of the plate 34 than the port 71, while the outer ends of the ports 72 and the ports 71 are spaced substantially equal distances from the center of the plate. In other words, the outer end portions of the ports 71 and 72 are arranged to alternately communicate with the fluid passages 73 and 74, while the inner ends of the ports 71 and 72 are arranged in permanent communication with the piston chambers 40 and 44, respectively, as indicated more particularly in Figure 3.

The fluid passages 73 and 74 are each adapted to function as an inlet or discharge passage and are formed in the following novel manner:

An annular plate or ring 76 is positioned in a corresponding annular recess 77 provided in the inner face of the casing end plate 23. The ring or plate 76 is provided with a pair of openings 73' and 74' arranged at diametrically opposite sides thereof so as to alternately communicate with the outer end portions of the ports 71 and 75

12. The plate 76 is provided with a pair of sleeves 78, one for each opening 73' and 74'.

The sleeves 78 may be secured in any suitable manner, as by welding, to the outer face of the plate 76 with the interior thereof in registration with the openings 73' and 74' respectively. The sleeves 78 extend outwardly from the plate 76 through suitable openings 78' provided in the casing side plate 23 and stuffing boxes 79 connected with the case plate to a short distance beyond the stuffing boxes. The outer ends of the sleeves 78 may, as shown in Figure 6, be externally screw-threaded for receiving a flange 80 to which fluid conduits, as 81 and 82 (Figure 1), are connected for conveying fluid to and from the passages 73 and 74. The sleeves 78 are slidably mounted in the opening 78' so that the ring 76 may be moved inwardly into close sliding fit with the adjacent outer surfaces of the rotor end plate 34.

In order that the plate 76 may be adjusted toward the rotor plate 34 to compensate for wear, a plurality of, in this instance four, screws 84 are screw-threaded in the case end plate 23 for contacting the outer surface of the plate 76, as illustrated more particularly in Figures 7 and 13. A lock nut 85 may be mounted on each screw 84 for securing the screw in the adjusted position. The openings 73' and 74' in the plate 76, as illustrated in the drawings, are substantially circular in cross section and the plate 76 is provided with a pair of channels 86 and 87 in the inner face thereof which extend outwardly from the inner adjacent sides of the openings 73' and 74' in substantially parallel relation with each other.

The channels 86 and 87 are spaced from the axis of the plate 76 a distance substantially equal to the spacing of the ports 71 and outer ends of the ports 72 from the axis of rotation of the rotor 31 so as to lie in the plane of said ports and alternately register therewith during the rotation of the rotor 31, as indicated diagrammatically in Figures 8, 9 and 10.

The pistons 41 and 42 may be of such width that they will have a close sliding fit in the piston chambers 40 and 44, respectively. However, it is preferable that the pistons be so constructed that the width thereof is less than the corresponding dimension or thickness of the piston chamber in which they are mounted, as indicated in Figure 3, and that the pistons be provided with pressure plates or shoes 88 and 90 for maintaining the pistons in fluid-tight connection with the walls of the piston chambers extending parallel with the direction of reciprocative movement of the pistons. These pressure plates or shoes, as shown more particularly in Figures 3 and 14, are substantially rectangular flat members of less width than one half the width of the side of the piston to which they are connected and are of substantially the same length as the piston.

Each plate or shoe is provided with a laterally extending rib 91 at one side thereof which extends longitudinally of the shoe or plate substantially midway between the longitudinal edges thereof. The rib 91 is substantially semi-circular in cross section and is received in a semi-circular socket 92 provided in the wall of the piston, as shown in Figure 3.

The outer surfaces of the plates or shoes 88 and 90 are adapted to slidably contact with the adjacent wall of the respective piston chamber 40 or 44, while the ribs 91 are rotatably received

in the respective sockets 92 and maintain the plates or shoes slightly spaced from the adjacent surface of the corresponding piston to permit limited rocking movement of the shoe with respect to the piston as torque is applied to the pistons and at the same time maintain a substantially fluid-tight connection between the piston and the wall of the piston chamber.

The operation of the pump shown in Figures 1 to 12, inclusive, will now be understood to be substantially as follows:

Assuming that the control shaft 50 is at its innermost position with the guide block registering in the upper portion of the opening 47, as indicated in Figures 2, 3, 6, 11 and 12, and that the shaft 27 is rotated in a clockwise direction, as viewed in Figures 3, 11 and 12. It will now be observed that the inner piston 42 which is mounted upon the bearing sleeve 46 symmetrically therewith will rotate about said sleeve and, inasmuch as the piston chamber 40 revolves about the bearing sleeve in eccentric relation thereto, the piston 42 will have a reciprocative movement with respect to the piston chamber 40 in a direction at right angles to the plane passing through the axes of the rotor 31 and bearing sleeve 46 when the pistons and piston chambers are in the positions illustrated in Figure 3.

In a similar manner, the outer piston 41 which is mounted on the inner piston 42 in substantially symmetrical relation with the bearing sleeve 46 and, therefore, in eccentric relation with the piston chamber 40, will rotate about the axis of the bearing sleeve 46 and, therefore, in eccentric relation with the axes of rotation of piston chamber 40, rotor 31, control shaft 50 and drive shaft 27. This causes relative reciprocative movement of piston 41 and chamber 40 in a direction substantially normal to the direction of relative reciprocative movement of piston 42 and chamber 44. When piston 41 is positioned adjacent one end of the piston chamber 40, as illustrated in Figure 3, rotation of the rotor in a clockwise direction one-quarter of a revolution will cause the piston 41 to move to a position substantially midway between the ends of the chamber 40, as illustrated in Figure 12. As the rotor 31 continues in a clockwise direction through the second quarter of a revolution, the end of the chamber 40 which was previously spaced upwardly from the piston will be substantially in contact with the piston at the lower side thereof, thereby producing a discharge stroke at the end of the piston chamber 40 which is uppermost in Figure 3, and a suction stroke at the end of the piston chamber which is lowermost in Figure 3.

During the rotation of the rotor 31 and the pistons mounted therein, the fluid passages 73 and 74 will be alternately brought into communication with the piston chambers 40 and 44 by the registration of the ports 71 and 72 with the passages and with the channels 86 and 87 associated with said passages. To explain more explicitly, it will be observed that when the pistons 41 and 42 are in the positions illustrated in Figure 3, the ports 71 and 72 will be in the positions illustrated in Figure 8, that is, the ports 71 which are in registration with the ends of the piston chamber 40 at opposite sides of the piston 41 are positioned at opposite ends of the channels 86 and 87 out of communication with said channels and, therefore, with the passages 73 and 74. The ports 72 which have the inner ends thereof in communication with the ends

of the piston chamber 44 at opposite sides of the piston 42 have the outer ends thereof in registration with the channels 86 and 87 and, therefore, with the passages 73 and 74. As the rotor 31 is rotated one-eighth of a revolution in a clockwise direction, the ports 71 and 72 will move from the position shown in Figure 8 to that shown in Figure 9. That is, the ports 71 will be in registration with the passages 73 and 74, respectively, while the ports 72 continue to remain in registration with said passages or with the channels 86 and 87 associated therewith.

It will thus be seen that during the movement of the rotor from the position shown in Figure 3 one-eighth of a revolution to the position shown in Figure 11, the piston 42 which is located substantially midway between the ends of the piston chamber 44 in Figure 3 will have moved toward the end of the chamber 44 adjacent the fluid passage 74, thereby increasing the area of the space between the piston and the end of the piston chamber in communication with the passage 73 and thereby producing a suction at said end of the piston chamber for drawing fluid through the inlet passage 73 and port 72 into said piston chamber.

Similarly, the opposite end of the piston chamber 44 which is in communication with the passage 74 will have decreased in area so that fluid contained in said end of the piston chamber will be forced outwardly through the port 72 registering with the passage 74 into said passage. Simultaneously with this action of the piston 42, the outer piston 41 will move from the position shown in Figure 3 adjacent the lower end of the piston chamber 40 toward the opposite end thereof, thereby producing a suction in the end of the piston chamber 40 which is in registration with the inlet passage 73 for drawing fluid through said passage and the port 71 registering therewith into said end of the piston chamber 40. At the same time, fluid contained in the opposite or upper end of the piston chamber 40 will be forced outwardly through the port 71 registering with the channel 86 associated with the passage 74 into said passage.

As the rotor continues movement in a clockwise direction through the next one-eighth of a revolution, the pistons 41 and 42 will move from the position shown in Figure 11 to that shown in Figure 12. In other words, relative movement of the piston 41 and piston chamber 40 will cause piston 41 to move to a position substantially midway between the ends of the chamber 40. At the same time, relative movement of the piston 42 and piston chamber 44 will have been effected so that the piston 42 will be positioned at one end of the chamber 44. At the same time, the ports 71 and 72 will move from the position shown in Figure 9 to that shown in Figure 10. In other words, the ports 71 will remain in registration with the fluid passages 73 and 74, respectively, for maintaining the ends of the piston chamber 40 in communication with said passages, respectively, while the ports 72 will have moved out of registration with said passages with the result the ends of the piston chamber 44 will be cut off from communication with the passages 73 and 74.

At the beginning of the next half revolution of the rotor 31, ports 72 will move into registration with the channels 86 and thereby bring the ends of the piston chamber 44 into communication with the passages 73 and 74, respectively. As piston 42 and the piston chamber 44 are moved

with respect to each other, fluid from the inlet passage 73 will be drawn into one end of the piston chamber 44 while fluid in the opposite end of the piston chamber 44 will be forced outwardly through the discharge passage 74.

During the second half revolution of the rotor 31 the ports 71 will remain in communication with the corresponding passages 73 and 74 until near the end of the complete revolution of the rotor when said ports will move out of registration with the ports and channels associated therewith and cut off communication of the piston chamber 40 with the passages 73 and 74. These cycles of operation of the piston chambers and ports may continue as long as the rotor is operated for drawing fluid into the piston chambers from the inlet passage 73 and discharging the same from the piston chambers outwardly through the discharge passage 74.

When the control shaft 50 is in its innermost position, as illustrated in Figure 2, the pistons 41 and 42 and piston chambers 40 and 44 will function at maximum capacity. If, for any reason, it is desired to reduce the capacity of the pump, this may be readily accomplished by producing outward axial movement of the control shaft 50 through the medium of the lever 63. Outward movement of the shaft 50 causes the pins 67 and slots 69 to function with a cam action for producing lateral movement of the bearing sleeve 46 with respect to the supporting block 48 and thereby gradually move the axis of the bearing sleeve toward the axis of rotation of the rotor 31 until said axes coincide, at which time the control shaft 50 will be at the end of its extreme outward movement. As the axis of the bearing sleeve thus approaches the axis of rotation of the rotor, the degree of relative movements of the pistons 41 and 42 and the cylinders 40 and 44 will gradually decrease and thereby decrease the volume of fluid caused to pass through the pump until the axis of the bearing sleeve coincides with the axis of rotation of the rotor when the degree of relative reciprocative movements of the pistons and piston chambers will cease altogether and the pumping action thereof is discontinued.

When it is desired to again increase the capacity of the pump, this may be readily accomplished by moving the control shaft 50 inwardly so as to again move the axis of the bearing sleeve 46 into eccentric relation with the axis of rotation of the rotor 31. The degree of inward movement of the control shaft 50 and the amount of eccentricity of the axis of the bearing sleeve 46 and rotor 31 determines the capacity of the pump or the volume of fluid forced therethrough.

When it is desired to reverse the direction of flow of fluid through the pump without reversing the direction of rotation of the rotor 31, this may be readily accomplished by rotating the control shaft 50 one-half revolution. This rotation of the bearing sleeve 46 with respect to the piston 42 journaled thereon will reverse the positions of the pistons 41 and 42 with respect to the chambers 40 and 44. In other words, instead of the piston 41 being adjacent the lower end of the piston chamber 40, as shown in Figure 3, said piston will be positioned at the upper end of said chamber while the piston 42 will remain positioned substantially midway between the ends of the chamber 44. As the rotor 31 is now rotated in a clockwise direction, the pistons and piston chambers will function in reverse order to that above described so that fluid will be drawn in-

wardly through the passage 74 and discharged outwardly through the passage 73.

It will be understood that the capacity of the pump may be varied after the control shaft 50 has been rotated to bring the axis of the bearing sleeve 46 above or at the opposite side of the axis of rotation of the rotor 31 from that shown in Figure 3 by producing longitudinal movement of the control shaft 50 and varying the amount of eccentricity of the bearing sleeve with respect to the axis of the rotor as explained above.

In Figures 15, 16, 17 and 18, I have illustrated a pump which functions in substantially the same manner as that shown in Figures 1 to 12, inclusive, with the exception that the capacity of the pump cannot be varied and the direction of operation cannot be changed without changing the direction of rotation of the drive shaft or the rotor. In the construction shown in these figures, the drive shaft, as 27', extends through the interior of the pump in eccentric relation to the case chamber 30' and has the inner end thereof journaled in a suitable bearing member 25' provided on the case end plate 22'.

Furthermore, the inner piston, as 42', is mounted directly on the shaft 27' and secured thereto as by a key 95 so that rotary motion of the drive shaft 27' is transmitted directly to the piston 42'.

30 In the recesses 96 are rotatably mounted, as upon pins 97, rollers 98 which project slightly beyond the peripheral surface of the side flanges 99 defining the recess 96 into rolling contact with the peripheral surface of the case chamber 30' for rotatably supporting the rotor 31' in said chamber. The rotor 31' is provided with a piston or compression chamber 40' in which is mounted for reciprocative movement a piston 41'. The piston 41' is provided with a piston or compression chamber 44' which receives the piston 42' therein.

Rotation of the shaft 27' and piston 42' transmits rotary motion through piston 41' to the rotor 31' mounted in the rotor chamber 30' of the case 20'. The rotor 31', in this instance, is a unitary member having four recesses 96 provided in the periphery thereof arranged in substantially uniform circumferential spaced relation to each other.

50 The case 20' is provided with an inlet passage 100 and an exhaust passage 101 formed in laterally disposed bosses 102 and 103 connected with the side plate 23' on the case 20'. The passages 100 and 101 are in communication with the rotor chamber 30' and, therefore, in direct communication with the piston or compression chambers 40' and 44' which, in this instance, are always in direct communication with the side plates 22' and 23' of the case 20'.

60 The inlet and exhaust passages are each provided with laterally disposed channels 104 formed in the side plate 23' at the inner end of the passages. These channels 104 extend outwardly in opposite directions from the corresponding passage so as to be in communication with the piston chamber 40 and 44 during all but a relatively small portion of the rotary movement of the piston chambers and rotor 31', as indicated in Figures 16, 17 and 18. In other words, the length of each channel 104 is such that the two fluid passages 100 and 101 will not be brought into communication with each other by either of the piston chambers 40' and 44' during the rotation of these chambers.

However, the channels 104, like channels 86, are of such a length that when the piston chambers extend in substantially parallel relation with the channels, with the corresponding piston positioned at one end of the chamber, as shown in Figures 16 and 18, but a slight rotary movement of the chambers is necessary to bring said chambers into communication with one or the other of the channels for connecting said chambers with the inlet and exhaust passages and thereby eliminate back pressure in the chambers and contribute to the smooth, noiseless operation of the pump.

In operation, instead of the rotor 31' being driven directly from the source of power as in the case of the structure shown in Figures 1 to 3, inclusive, the power is applied directly to the inner piston 42' from the shaft 27'. It is thus seen that the piston 42' transmits rotary motion to the piston 41' which in turn produces rotary motion of the rotor 31'. Rotation of the pistons and piston chambers produced by the shaft 27' causes relative reciprocative motions of the pistons and their respective chambers due to the circular motions of the piston 42' and the rotor 31' about axes arranged in eccentric relation with respect to each other. These relative reciprocative movements of the pistons and their chambers causes them to function with a positive action for drawing fluid, such as water or air, through the inlet passage 100 and forcing the same outwardly through the discharge passage 101.

While I have illustrated the pistons 41' and 42' as having direct sliding contact with adjacent side walls of the corresponding chambers 40' and 44', it will be obvious that these pistons may be provided with the compression plates or shoes 89, as shown and described for the structure illustrated in Figure 3 of the drawings.

Although I have shown and particularly described the preferred embodiments of my invention, I do not wish to be limited to the exact construction shown as various changes both in the form and relation of the parts thereof may readily be made without departing from the spirit of the invention as set forth in the appended claims.

I claim:

1. In a device of the character described, a case having a rotor chamber therein, a rotor mounted in said chamber having a fluid compression chamber, fluid conveying means connecting said latter chamber with the exterior of the case comprising a contact member mounted in the case adjacent the rotor, fluid conduit means connected with the contact member and extending outwardly through the case, said conduit being adapted to intermittently communicate with the fluid compression chamber during the rotation of the rotor, and means associated with the case and with said fluid conveying means for urging said contact member into contact with the adjacent surface of the rotor.

2. In a fluid pump or motor of the class wherein a rotor is mounted in a case to have an axis of rotation, and a pair of pistons are mounted one within the other in a piston chamber provided in the rotor to reciprocate in directions normal to each other, the combination with said case, rotor and pistons of a control member mounted in the case substantially coaxially with the rotor for both reciprocative and rotative movements with respect to said case, a bearing member mounted in the rotor independently of the case rotatably supporting the innermost one

of said pistons, a supporting member rotatably mounted in the rotor coaxially therewith, means operatively connecting the control member to the supporting and bearing members to rotate said latter members in unison upon rotation of the control member to bring the axis of rotation of said innermost piston from a position at one side of the axis of rotation of the rotor to a position at the opposite side of said axis, said connecting means including drive and driven elements connected with the control and bearing members respectively coacting upon reciprocative movement of the control member to produce lateral movement of the bearing member toward and from the axis of rotation of the rotor.

3. In a fluid pump or motor of the class wherein a rotor is mounted in a case to have an axis of rotation, and a pair of pistons are mounted one within the other in a piston chamber provided in the rotor to reciprocate in directions normal to each other, the combination with said case, rotor and pistons of means rotatably supporting the innermost ones of said pistons in adjustable relation with respect to said axis of rotation of the rotor comprising a supporting member journaled in the rotor substantially coaxial therewith, a control member mounted in the supporting member for both rotative and reciprocative movements with respect thereto, a bearing element rotatably supporting said innermost piston and mounted upon the supporting member for movement relative thereto substantially normal to the axis of rotation of the rotor, means including pin and slot connections between the control member, supporting member and the bearing element adapted upon rotation of said control member to effect rotation of the bearing element and supporting member about the axis of the rotor independently of the rotary movement of said rotor, said pin and slot connections between the control member and the bearing element being so constructed and arranged that said bearing element is moved with respect to the supporting member toward and from the axis of rotation of the rotor upon reciprocative movement of said control member.

4. In a fluid pump or motor, a case having inlet and discharge passages, a rotor journaled in the case, said rotor having end walls and a cylindrical body portion interposed between said end walls defining a substantially fluid-tight piston chamber, a pair of pistons mounted in said piston chamber one within the other to reciprocate in directions normal to each other, bearing means carried by said rotor adapted to support the innermost one of said pistons in eccentric relation with respect to the axis of rotation of the rotor, said rotor having two pairs of inlet and outlet ports, one pair for each piston, the ports of each pair being arranged in one or both of said end walls adapted to successively register with the inlet and discharge passages respectively upon rotation of the rotor, and means for effecting rotation of said rotor.

5. In a fluid pump or motor, a case having inlet and discharge fluid conveying means, a rotor journaled in the case, said rotor having a substantially fluid-tight piston chamber therein, a pair of pistons mounted in said piston chamber one within the other to reciprocate in directions normal to each other, bearing means carried by said rotor adapted to rotatably support the innermost one of said pistons in eccentric relation with respect to the axis of rotation of the rotor, said rotor having two pairs of inlet and

Outlet ports, one pair for each piston, said ports being arranged in one of the end walls of the rotor to successively register with the inlet and exhaust fluid conveying means respectively upon rotation of the rotor, said inlet and discharge fluid conveying means comprising a contact member mounted in the case adjacent said end

wall of the rotor, fluid conduit means operatively connected to the contact member and extending outwardly through the case, and means for urging said contact member into frictional engagement with said end wall of the rotor.

5

MAYNARD E. ESTEY.
